UNITED STATES PATENT OFFICE.

WILLIAM H. KREMSE, OF OMAHA, NEBRASKA.

PLOW ATTACHMENT TO WAGON-GEARING.

SPECIFICATION forming part of Letters Patent No. 276,975, dated May 1, 1883.

Application filed July 24, 1882. (No model.)

To all whom it may concern:

Be it known that I, WILLIAM H. KREMSE, of Omaha, in the county of Douglas and State of Nebraska, have invented a new and useful Improvement in Mechanism for Attaching Plows to Wagon-Gearing, of which the following is a full, clear, and exact description.

Reference is to be had to the accompanying drawings, forming a part of this specification, in which similar letters of reference indicate corresponding parts in all the figures.

Figure 1 is a perspective view of my improvement, shown as applied to the rear part of a wagon-gearing. Fig. 2 is a perspective view of the forward part of the plow-beam. Fig. 3 is a sectional plan view of one of the adjusting-slides and its guide-bars.

The object of this invention is to form sulky-plows by connecting ordinary plows with the running-gearing of wagons.

The invention consists in a mechanism for attaching plows to wagon-gearings, constructed with two pairs of upright tongued bars secured to the axle and bolster of a wagon-gearing by a plate placed upon the forward side of the said axle and bolster, clamping-blocks placed upon the outer sides of the lower ends of the upright bars, and clamping-bolts placed above and below the said axle and bolster. Upon the upright bars slide blocks, to which is hinged the bail, connected with the plow-beam by clamping plates and bolts. The sliding blocks are connected by hinged bars with bent levers, which are provided with pawls and catch-bars, so that the plows can be readily adjusted and controlled, as will be hereinafter fully described.

I will describe my improvement as applied to the rear part of a wagon-gearing, but the forward part of a wagon-gearing can be used if desired.

A represents the wheels, B the axle, C the bolster, and D the stakes, of the rear part of an ordinary wagon-gearing.

E are upright bars, two pairs of which are used, and which are secured at a little distance apart to the rear side of the axle B and bolster C. The upper parts of the bars E are secured in place by bolts F, which pass through them at the upper side of the bolster C, and through a plate, G, placed against the forward side of

the bolster C and axle B. The outer sides of the lower parts of the bars E are corrugated transversely to correspond with the corrugations formed in the inner sides of two clamping-blocks, H, one for each pair of bars E.

I are bolts which pass through the centers of the clamping-blocks H and through the plate G below the axle B.

Upon the adjacent sides of the bars E of each pair are formed ribs or tongues J, which fit into corresponding grooves K, formed in the opposite sides of the sliding blocks L, so as to keep the said blocks in place as they move up and down.

To a lug formed upon the outer side of the upper end of each sliding block L are hinged the lower ends of two short bars, M, or the forked end of a single bar. The upper ends of the bars M are hinged to the rear arms of the bent levers N at a little distance from their angles. Each lever N is pivoted at its angle to and between the upper ends of the bars E by a bolt, O.

To the lower parts of the sliding blocks L are swiveled eye-bolts P, to the eyes of which are hinged the hooked ends of the bar or bail Q. The bar or bail Q is bent twice at acute angles, so that its straight middle part will be longer than the distance between the sliding blocks L, to allow the plow-beam R to be adjusted laterally to cut a wider or narrower furrow, as may be desired, and also to allow the attachment to be secured to the axle and bolster nearer to or farther from their centers, as may be desired.

To the upper and lower sides of the plow-beam R are secured plates S by bolts T, passing across the sides of the plow-beam R and through lugs formed upon the end parts of the side edges of the said plates. The lugs of the plates S are slotted to receive the bolts T, so that the clamping-plates S can be applied to wide and narrow plow-beams with equal facility.

To the middle part of the upper plate, S, is bolted a cap-plate, W, which forms therewith a bearing for the middle part of the bar or bail Q. The clamp-bearing S T W is kept in place adjustably upon the bail Q by collars V, placed upon the said bail and secured by screws W.

To the rear arms of one the levers N is hinged

the forked upper end of the connecting-bar X, the lower end of which is secured by a bearing, Y, to the middle part of the bail Q.

With this construction, by operating the lever N placed at the land side of the plow and provided with the connecting-bar X the plow can be raised from and lowered to the ground, the other lever, N, being intended for leveling the plow or inclining it to one or the other side.

When the lever N is operated to raise the plow from the ground the plow is first turned toward the mold-board side of the plow, which causes the soil to slide off the said mold-board, and thus allows the plow to be raised more easily.

With each of the levers N is connected a pawl, Z, sliding in a guide-tube, a, attached to the lower part of the said lever N, and connected by a rod or chain, b, with a small bent lever, c, pivoted to the upper part of the said lever N. The pawls Z engage with the teeth of the catch-plate d, secured to the rabbeted inner side of the upper end of the inner end of the inner-bars E.

e is the driver's seat, the lower end of the standard f of which is secured to the bolster C and axle B by a socket or other suitable means.

Having thus described my invention, I claim as new and desire to secure by Letters Patent—

1. A mechanism for attaching plows to wagon-gearings, constructed substantially as herein shown and described, and consisting of the two pairs of tongued bars E and their fastening-plate and clamping-blocks and bolts G H F I, the sliding blocks L, connecting-bars M X, bent levers N, and the bail Q, as set forth.

2. In a mechanism for attaching plows to wagon-gearings, the combination with the axle and bars E and the sliding block L, of the bail Q, the hinged bars M X, the bent levers N, and rack-plates d, substantially as herein shown and described, whereby the plow can be readily adjusted and controlled, as set forth.

WILLIAM H. KREMSEER.
